UNITED STATES PATENT OFFICE

ALEXANDER M. PONIATOFF, OF PHILADELPHIA, PENNSYLVANIA, ASSIGNOR TO GENERAL ELECTRIC COMPANY, A CORPORATION OF NEW YORK

ELECTRICAL CONTACT STRUCTURE

Application filed February 7, 1930. Serial No. 426,678.

My invention relates to electrical contact structure, and more particularly to contact structure for switches of the large capacity, fluid-break type.

In circuit interrupters of large current carrying capacity, the dissipation of heat due to comparatively high resistance at the contacting surfaces presents a serious difficulty in switch design. In order to prevent the switch from "running hot" at its normal rated capacity, it is necessary to provide either an elaborate cooling system or to keep the resistance at the contacts within certain limits. This resistance may result from a number of causes, some of the more important being insufficient contact pressure and the formation of high resistance oxides on the contacting surfaces.

It is an object of my invention to provide an improved switch contact structure for maintaining the resistance, and consequently the heating, at the switch contacts within comparatively low limits thereby increasing the effective current carrying capacity of the switch.

It is a further object of my invention to provide an improved switch contact structure for maintaining a substantially constant bearing pressure between the contact surfaces of the switch and for precluding the formation of high resistance oxides at said surfaces.

It is a further object of my invention to provide an improved switch contact which shall be simple and easily constructed, and which shall present a low resistance path for current traversing the same.

My invention will be more fully set forth in the following description, referring to the accompanying drawings, and the features of novelty which characterize my invention will be pointed out with particularity in the claims annexed to and forming a part of this specification.

Referring to the drawings, Fig. 1 is an elevational view, partly in section, of circuit interrupting apparatus embodying my invention; Fig. 2 is an enlarged view, partly in section, of structure illustrated in Fig. 1,

and Fig. 3 is a view taken along the line 3—3 of Fig. 2.

Fig. 1 illustrates a circuit interrupter of the fluid-break type comprising a tank or housing 1 for containing an insulating and arc-extinguishing medium 2, such as oil, within which the movable parts of the switch structure are immersed. The terminal or stationary part of the switch structure comprises a pair of conductor studs 3 mounted within and secured with respect to the top wall of an upper section 1' of the switch housing. The usual insulating bushings 4 serve to insulate the conductor studs from the circuit breaker housing, and the bushings are in turn secured in any suitable manner, as by the clamping flanges 4', to the housing. The conductor studs 3 are hollow and provided with ventilating tubes 5 for removing heat from the interior of the studs, this arrangement being described and claimed in my co-pending application Serial No. 426,677, filed February 7, 1930, forming no part of the present invention.

Mounted and electrically connected to the lower end of each conductor stud 3 is the stationary contact structure of the switch, the same being disposed beneath the oil level as illustrated. The lower end of the conductor stud comprises a pair of flange-like portions 6 at opposite sides of the tubular stud, at the end of which a V-shaped slit or notch is formed. This construction permits the switch contact structure to be connected directly to the conductor stud without the usual adapter generally interposed between the conductor stud and contact. Due to the fact that the adapter introduces additional resistance in the switch structure and increases the construction costs, the elimination thereof is obviously advantageous.

Referring to Fig. 2, the contact structure connected to each conductor stud comprises a plurality of laminæ 8 of conducting material such as copper, for example, stacked together in the usual sheaf fashion and forming an open loop.

The opposite ends of this loop, 9 and 10, are brazed or hot pressed so as to form a substantially solid, uniformly conducting por-

tion. In the present instance the laminæ are solidified to form a uniformly conducting portion by first tin-plating, or otherwise coating with a suitable brazing metal, each individual lamina throughout its length corresponding to the length of the portion to be solidified, and thereafter applying pressure to compress the laminæ in the presence of heat. The heat for the brazing process may be applied either by passing an electric current through the laminæ to be brazed or by placing the same within a vacuum furnace, the pressure, of course, being maintained. After a suitable period the brazed portion is 10 permitted to cool. The laminæ are so integrally united by this process that it is almost impossible to detect by ordinary inspection of a cross-section of the brazed portion any indications of the individual lamina. Accordingly, the electrical resistance throughout the brazed portion is substantially the same as in a solid conducting portion. It will be apparent at this point that other suitable processes or methods for producing a solid, 20 uniformly conducting section at the opposite ends of the laminæ may be employed. The solid portions 9 and 10 are secured and electrically connected to the flanges 6 of the conductor stud in any suitable manner, as by the 30 clamping plates 11 and through bolts 12. A spacing member 13 is mounted between the flanges 6 and serves as a guide for a rod 14 freely slideable therein, and secured at its lower end, as by screw-threaded engagement 35 to a pressure plate 15. Resilient means, as a coil spring 16, is seated within the loop at one end on stationary structure of the conductor stud and serves to bias the pressure plate 15 against the inner side of the loop 40 contact so as to exert an expansive action thereon. A stop or limit nut 14' is carried by the rod 14 to maintain the movement thereof within predetermined limits.

A section of the laminæ comprising the 45 loop substantially opposite the pressure plate 15 is likewise brazed or suitably treated to produce a solid, uniformly conducting portion 17 to which a contact plate 18 is pressure brazed as in the manner previously described. The pressure plate 15 may be connected to the 50 inner portion of the loop in any suitable manner as by the screws 19.

The contact plate 18 is preferably electrically connected to the portion 17 by brazing 55 so that it forms a substantially integral and uniformly conducting part thereof, thereby reducing the resistance of the union. The contact plate is of material whose oxide has a lower resistance than the oxide of the material comprising the laminæ of the loop contact. In the present instance the material of the contact plate is of silver whose oxide is of considerably lower resistance than the copper oxide of the laminæ 8. The contact plate 18 is preferably flat, and as illus-

trated in Fig. 3, may be knurled or otherwise machined, so as to prevent an oil film from existing between the contacting surface of the plate and its coacting butt contact. When the relatively movable contact surfaces 70 are brought together, an oil film at first exists between the coacting surfaces, and it is the function of the knurls, or slots, to permit dissipation and removal of the film within a very short time after pressure is applied to 75 the contacts.

When the contact surfaces are very close together and separated only by the oil film, the film is broken by arcing between the contacts, thereby establishing the current. Since 80 it is essential that the duration of this arcing be decreased to a minimum in order to reduce burning of the contacts, the oil film should be gotten rid of as quickly as possible so that the contacting surfaces may be 85 brought together in metallic engagement with each other. In the present instance the oil film flows out from between the contacting surfaces very quickly during closure of the contacts so that burning of the surfaces thereof is minimized. 90

The coacting contact of the switch comprises a bridging member 20 adapted to be raised or lowered by suitable means within the switch housing by an operating rod 21, and having at its opposite ends a contact plate 22 secured and electrically connected thereto in any suitable manner and corresponding in material and construction with its coacting butt contact 18. 100

It will be apparent that the copper laminæ may be formed as a continuous loop, in which case the portion of the loop opposite the contact portion would be brazed or otherwise solidified to form a uniformly conducting portion for suitable connection with a conductor stud. 105

The contact structure above described not only provides a low resistance path for current passing from the conductor stud to the solidified portions 9 and 10, the laminæ 8 and the contact portion 17, but permits the use of resiliently biased, flexible structure so that the pressure between the coacting contact surfaces may be maintained substantially constant, thereby maintaining the resistance due to this factor substantially constant. The maintenance of constant contact pressure is not possible when the resiliency of the copper laminations alone is depended upon. This is due to the fact that the resiliency of the copper varies with the temperature and in the case of flat, spring-like laminations, as in the brush type of contact, for example, a permanent set may occur so that readjustment would be necessary in order to restore the proper contact pressure. The use of the silver contact plate serves to materially reduce the contact resistance since, as previously explained, the silver oxide 110 115 120 125 130

which may form on the contact surface is of lower resistance than copper oxide and moreover the silver oxidizes much more slowly than copper.

5 When the circuit interrupter is in its closed position, as illustrated in Fig. 1, the movable bridging member 20 presses the contact plate 22 into butt engagement with the coating contact plate 18 so that the 10 spring 16 is placed under compression. Accordingly, the bearing pressure between the contact surfaces is not necessarily dependent on the exact position of the bridging member 20, but is dependent on the spring 16 15 whose tension may be adjusted in any suitable manner.

When the switch is traversed by heavy short circuit currents or overloads, the bridging member 20 is acted upon by electro-magnetic forces tending to repel the movable contacts in a downward direction. If it is desirable for the switch to remain closed during these heavy currents, it is also desirable that the contact resistance shall not increase 25 and that the contact pressure be maintained substantially constant. For the purpose of compensating for a certain amount of yielding of the mechanism holding the bridging member in its closed position, the compression spring 16 is adjusted to have an initial 30 tension so that the contacts are maintained together at substantially constant pressure even though the bridging member is repelled to a certain extent by the forces set up by the 35 heavy currents. In the same manner, during closing movement of the switch, the compression spring will provide substantially constant pressure between the contact surfaces, practically from the time the movable 40 contacts carried by the bridging member first engage the coating contacts until they are disengaged therefrom.

It will be noted that the path of the current through the switch includes no high resistance unions such as where the current must flow transversely of the laminations. In each instance the electrical connection is 45 between solid uniformly conducting portions, the intermediate flexible laminæ affording equal resistance paths in parallel 50 for the current. Engagement of the contact surfaces of the switch permits the contact surfaces to be pressed together so that the contact resistance may be roughly estimated from the actual contact area and the bearing pressure exerted by the spring 16.

It shall be understood that the term "brazed" as used in the specification and following claims, is to include any operation 60 for merging the laminæ at any portion of the loop into a solid, uniformly conducting section.

It shall be further understood that my invention is not limited to the specific details of construction and arrangement thereof herein

illustrated, and that changes and modifications may occur to one skilled in the art without departing from the spirit of my invention.

What I claim as new and desire to secure 70 by Letters Patent of the United States is:

1. In a circuit interrupting apparatus, switch contact structure having large current carrying capacity comprising a plurality of laminæ of conducting material arranged in the form of an open loop, the laminæ at the ends of said loop being brazed to form a substantially solid conductor for electrically connecting the contact structure in a circuit, and a contacting portion disposed 75 intermediate the ends of said loop, said contacting portion comprising a brazed section of the laminæ to form a substantially solid and uniformly conducting portion.

2. In an oil circuit breaker, switch contact structure having large current carrying capacity comprising a plurality of leaf shaped laminæ of conducting material in the form of an open loop, the sides of said loop being formed of the flexible laminæ 90 and the opposite ends of the loop and lower part thereof forming the contact surface being brazed to form solid, uniformly conducting portions.

3. In circuit interrupting apparatus, 95 switch contact structure having high current carrying capacity comprising a plurality of leaf-like laminæ of conducting material arranged in the form of an open loop, the free ends of said loop connected to terminal structure, and a contact plate of material less subject to oxidation than that of said conducting material electrically connected to the laminæ at an outer side of said loop forming a contact surface thereon. 100

4. In circuit interrupting apparatus, switch contact structure comprising a plurality of leaf-like laminæ of copper, said laminæ brazed at one section to form a solid 110 uniformly conducting portion, and a silver plate electrically connected to said portion forming a contact surface on said laminæ.

5. In a circuit interrupting apparatus, switch contact structure comprising a plurality of laminæ of conducting material in the form of an open loop, the laminæ at the opposite ends of said loop being brazed to form solid, uniformly conducting portions, clamping means for electrically connecting said portions to a conductor stud, a silver 115 contact surface at the outer side of said loop electrically connected to said laminæ, a relatively movable silver contact surface coating therewith, and a spring disposed within said loop for biasing the laminæ toward said 120 second contact surface thereby establishing substantially constant bearing pressure and electrical resistance between the coating contact surfaces.

6. The combination with a fluid break 130

switch comprising relatively movable contact structure adapted to operate within an insulating fluid, of means for maintaining the bearing pressure and electrical resistance between the contacting surfaces of the switch substantially uniform comprising a contact member formed of laminæ of conducting material in the shape of a loop, the laminæ at one part of the loop being brazed to form a solid, uniformly conducting portion, a silver plate electrically connected to said portion at the outer side of said loop forming thereon a contact surface, a relatively movable silver contact surface coacting therewith, and a spring disposed within said loop for pressing together said contact surfaces at substantially constant pressure when the switch is in its closed circuit position.

7. In a circuit breaker comprising relatively movable butt contacts, contact structure comprising a sheaf of laminæ of conducting material in the form of a loop connected at opposite ends to a conductor stud, a section of said loop being brazed to form a solid, uniformly conducting portion having a butt contact surface on the outer side of said loop.

In witness whereof, I have hereunto set my hand this 29th day of January, 1930.

ALEXANDER M. PONIATOFF.
